UNITED STATES PATENT OFFICE.

EDWARD H. MOYLE, OF LOS ANGELES, CALIFORNIA.

ROCK-CRUSHER.

1,142,116.

Specification of Letters Patent. Patented June 8, 1915.

Application filed March 2, 1914. Serial No. 821,954.

To all whom it may concern:

Be it known that I, EDWARD H. MOYLE, a citizen of the United States, residing at Los Angeles, in the county of Los Angeles and 5 State of California, have invented a certain new and useful Improvement in Rock-Crushers, of which the following is a specification.

My invention relates to a crusher and pulverizer for rocks and ores.

Objects of this invention are to provide a device for effectively reducing the rock or ore to a condition desired by successive stages, consisting in first breaking the rock 15 or ore along the lines of least cleavage, then crushing the same and finally transforming the same into a pulverulent mass of a desired mesh; to provide a simple device made of the fewest parts, readily dissociable; having a minimum of bearings, convenient for transportation into difficultly accessible places, and quickly assembled; to provide a crusher in which the degree of fineness of the ore or rock may be regulated during the 25 operation of the same, and finally to provide a device in which no material damage will be occasioned by the entry of any substance harder than that calculated for the crushing power of the jaws.

With these and other objects in view, this invention consists of the features, and details of construction, separately and in combination, described in connection with the accompanying drawings, and then more particularly pointed out in the claims.

In the drawings, Figure 1, is a side elevation of the crusher, one of the plates being removed to disclose parts otherwise hidden. Fig. 2, is a side elevation of the assembled 40 crusher. Fig. 3, is a sectional detail on lines 3—3, Fig. 1, showing the strut connection with the swinging lever. Fig. 4, is a perspective detail of the removable shoe. Fig. 5, is a perspective detail of the die plate. 45 Fig. 6, is a plan view. Fig. 7, is an end view showing the breakable strut or thrust and the adjusting means therefor. Fig. 8, is an end view showing a modified form of the adjusting means for the thrust, and Fig. 9 is a plan 50 view of the modified adjusting means.

In all, or nearly all, types of rock crushers, the base is a solid heavy casting, with many bearings, requiring expensive and careful machining, and with a multiplicity 55 of unequal strains, the weakest of which is

not perceptible until actual disruption occurs.

Generally the base in the ordinary class of crushers, consists of a massive sole plate, with weighty integral side and rear walls, 60 which with the other necessary adjuncts of the machine, makes a cumbersome product, difficult to transport, and more difficult, if not impossible to repair when fractured or broken.

In elimination of these disadvantages, the present invention consists of two side plates 1 and 2, having suitable flanges 3 and 4, on the bottom, provided with bolt holes 5 and 6, for fastening the same to a suitable supporting structure. These plates are tied together at one end by a shaft 7, and rod 8, carrying a spacer tube or pipe 9, and at the other end by a trunnion 10, the shaft 7, and trunnion 10, serving additional purposes to 75 appear hereinafter. Between and fulcrumed in said plates by fulcrum pin or shaft 11, which also serves to tie said plates, is a lever 12, of cross-sectionally U-shaped structure at one end, as seen in Fig. 3, embracing and 80 connected by a pin 13, with a strut 14, to which reciprocatory motion is imparted through the medium of an eccentric 15, turned or fastened on said shaft 7, which carries on the outside of said plates, the 85 usual fly wheels 16, and loose and fixed pulleys 17 and 18, respectively. The lever 12, as seen in Fig. 3, has a double bearing on the strut, whereby the friction is reduced to a minimum and the wearing life increased, the 90 pin 13, serving principally to connect the lever with the strut. On said lever 12, is removably fastened a crushing shoe 19, by counter sunk head bolts 19'. The plane of 95 said shoe is ribbed or corrugated for a portion of its length, as at 20, and terminates in a curve 21, at a point below said ribs or corrugations. The aforesigned trunnion 10, forms a pivotal support or bearing for a jaw 22, to which is arranged to be removably attached by countersunk bolts 23', a die plate 23, having a plane, ribbed or corrugated, as at 24, and terminating in a substantially compound or ogee curve 25, co-operating 100 with said curve 21, of said shoe 19, to levelate the rock or ore. The disposition of said shoe 19, and die plate 23, is in substantially the form of a Y, the crushing of the rock, fed from a hopper 26, immediately 105 above said shoe and die plate, proceeding 110

regularly and uniformly until the point between the oppositely disposed and interacting curves 21 and 25, is reached, where the final trituration takes place, and the finished product discharged below said shoe and die plate.

By reason of the corrugated planes of the shoe and die plate and the compound curves thereof, the rock or ore is crushed and powdered in successive steps to any desired mesh.

In the wider portion of the crushing chamber formed by the shoe and die plate, the crushing and breaking of the rock occurs by a reciprocatory motion of the lever, while the levigation of the rock occurs by a grinding motion of the curve of the shoe against the curve of the die plate, such motion being practically a circular one, since the lower end of the curve 21, of the shoe is virtually concentric, or nearly so, with the arc described by the movement of the lever around the fulcrum point, while the rest of the curve is eccentric to such arc.

Between the face of the lever 12, and the shoe 19, and also between the face of the jaw 22, and the die plate 23, is preferably interposed a lead filling or sheet, for the purpose of forming a perfect seat for the shoe and die plate, the rough and unplaned surfaces of which readily embed themselves into this plastic layer.

The die plate 23, normally rests on a shoulder 27, on the jaw 22, which as stated, is pivotally hung on the trunnion 10, and thus always connected in a pivotal manner with the side plates 1 and 2. The lower portion of said jaw, at the rear and at approximately a point opposite the compound curve of the die plate 23, is furnished with an integral abutment 28, which bears against a thrust bar 29, transversely disposed in elongated slots 30, and held in position by cotter pins 31, or in any other suitable manner. Adjustment of the thrust bar 29, to regulate the degree of fineness of the pulverized product, is effected by adjusting screws 32, extending longitudinally of each plate and locked in position of adjustment by lock nuts 33. The said thrust bar 29, may be of cast iron or any other material calculated to resist the strain incident upon the crushing of rocks and ores of ordinary hardness, but incapable of withstanding any excessive pressure, such as would result from the operation of the lever on metal substances or objects, as steel, iron, and the like, or in fact any, not intended for treatment by this machine. Should any objects accidentally or otherwise, fall between the shoe and the die plate in course of operation of the machine, the thrust bar will break, and permit the jaw to swing on its trunnion, thus insuring the other vital parts of the machine against breakage. The breaking of the thrust bar

at the critical moment of excessive strain, is of the utmost importance, since by so doing, the balance of the machine is preserved intact. Being of inferior material and intended for just such events, replacement of the same is coupled with no great expense, effort or labor. As is obvious, the adjustment of the thrust bar may be made during the operation of the crusher without affecting or hindering the process of pulverization.

In Figs. 8 and 9, I have illustrated a different form of adjusting means for the thrust bar, particularly for heavy duty and large machines, and consisting of the following: On the rear of said plates 1 and 2, is bolted or otherwise, fastened, a plate 34, having orifices for the accommodation of right and left hand screws 35 and 36, respectively, engaging threaded orifices extending inwardly from the rear of said plates into the slots 30, in which is disposed the thrust bar 29. On said screws 35 and 36, are keyed spur gears 37 and 38, between and in mesh with which is an operating gear 39, journaled on an arbor 40, suitably supported in said plate 34. Said spur gear 39, is provided with a bevel gear 41, with which is in mesh a bevel gear 42, pinned or keyed on the end of a shaft 43, mounted in a suitable support 44, said shaft having a key wrench receiving end 45, for operating the mechanism described in either direction, as required. The usual side liners 46, may be provided on the plates 1 and 2, suitable bolts serving to hold the same in position.

In making all necessary adjustments, it will be noted that the fulcrum of the lever is not disturbed, but remains in its once fixed position. It will also be noted that on account of the few parts and the readiness with which the same are assembled and disassociated, the whole machine may be made lighter and stronger than other machines now in use.

What I claim, is—

1. In a rock crusher, a plurality of spaced plates, means for connecting said plates, a stationary fulcrum shaft carried by said plates, a lever on said fulcrum shaft, a plate on said lever having a straight and curved face, the curve of said plate being for the greater part eccentric to said fulcrum shaft and concentric at the discharge end, means to operate said lever, a jaw trunnioned between said plates, a die plate on said jaw having a straight and curved face coöperating with the face of said plate on said lever and a thrust for said jaw.

2. In a rock crusher, a plurality of spaced plates, means for connecting said plates, a fulcrum shaft carried by said plates, a lever on said fulcrum shaft, means to operate said lever, a jaw trunnioned at its upper end and having its lower end hung free of and be-

tween said plates and capable of movement outwardly and beyond said plates, a thrust carried by said plates and in engagement with said free end of said jaw, and an adjusting means for said thrust.

3. In a rock crusher, a plurality of spaced plates, means for connecting said plates, a stationary fulcrum shaft carried by said plates, a lever on said fulcrum shaft, means 10 to operate said lever, a jaw trunnioned between said plates and capable of swinging outwardly beyond said plates, a transversely extending breakable means to hold said jaw stationary during operation of the crusher, 15 and means to adjust said breakable means to regulate the degree of fineness of the product crushed.

4. In a rock-crusher, a plurality of spaced plates, means for connecting said plates, a 20 stationary fulcrum shaft carried by said plates, a lever on said fulcrum shaft, a plate on said lever having a curve eccentric and concentric to said fulcrum shaft, means to operate said lever, a jaw trunnioned between 25 said plates, a plate on said jaw coöperating with the plate on said lever, and a thrust for said jaw.

5. In a rock crusher, a plurality of spaced

plates, means for connecting said plates, a stationary fulcrum shaft carried by said 30 plates, a lever on said fulcrum shaft, a shoe on said lever having a curve eccentric and concentric to said fulcrum shaft, means to operate said lever, a jaw trunnioned between 35 said plates and capable of being swung rearwardly and beyond said plates, a die plate on said jaw coöperating with said shoe, said die plate having a straight and curved face, a breakable means to hold said jaw stationary, and an adjusting means for said 40 breakable means.

6. In a rock-crusher, a plurality of spaced plates, a stationary fulcrum shaft in said plates, a lever on said fulcrum shaft, a shoe on said lever having a regular curve merging in an irregular curve, means to operate 45 said lever, a jaw trunnioned between said plates, a die on said jaw having a face corresponding with the face on said shoe, and means to adjust the lower end of said jaw. 50

In testimony whereof I affix my signature in the presence of two witnesses.

EDWARD H. MOYLE.
